UNITED STATES PATENT OFFICE.

ROBERT RAY ROTH, OF EASTON, MARYLAND.

MAIL CATCHING AND DELIVERING DEVICE.

No. 895,203.

Specification of Letters Patent.

Patented Aug. 4, 1908.

Application filed December 26, 1907. Serial No. 408,096.

To all whom it may concern:

Be it known that I, ROBERT RAY ROTH, a citizen of the United States, residing at Easton, in the county of Talbot and State 5 of Maryland, have invented a new and useful Mail Catching and Delivering Device, of which the following is a specification.

This invention relates to mechanism for delivering and receiving mail bags, and its 10 principal object is to provide novel means for supporting a bag from the side of a car, said means being capable of quickly releasing the bag upon moving into co-operative relation with a crane located at the side of the 15 track.

Another object is to provide bag holding means which will positively hold the bag against accidental release and the operation of which is in no sense retarded by the weight 20 of the supported bag.

A still further object is to provide novel means for holding the bag support extended beyond the wall of the car, said holding means being disposed to be released by the 25 means employed for releasing the bag.

A still further object is to provide means for receiving the bag from the crane, said means being mounted to swing under the impulse imparted to it by the engagement of 30 the moving bag therewith, there being mechanism employed, however, for initially retarding the rotation of the engaging means to insure the proper actuation of the bag releasing mechanism.

Another object is to provide mechanism of 35 this character which can be readily reversed so as to deliver or receive mail from the same side of the car when said car is moving in either direction.

A further object is to provide simple and 40 efficient means for locking the mechanism, which is upon the car, against the side of said car immediately subsequent to the delivery of a bag.

A further object is to provide means for 45 holding the bag against undesirable movement while supported by the delivery mechanism.

With these and other objects in view the 50 invention consists of certain novel features of construction and arrangement of parts, hereinafter fully described, illustrated in the accompanying drawings, and particularly pointed out in the appended claims, it being 55 understood that various changes in the form, proportions, size and minor details of

the structure may be made without departing from the spirit or sacrificing any of the advantages of the invention.

In the accompanying drawings: Figure 1 60 is a perspective view of the delivering and receiving mechanism, the bag being shown by dotted lines. Fig. 2 is an enlarged elevation of the bag supporting mechanism carried by the car, a portion of the bag being 65 removed and one of the bag engaging plates being broken away. Fig. 3 is an enlarged section on the line 3—3, Fig. 2. Fig. 4 is an elevation on line 4—4, Fig. 2. Fig. 5 is a section on line 5—5, Fig. 2. Fig. 6 is a de- 70 tail perspective view of bag engaging means used in connection with the delivering mechanism. Fig. 7 is an elevation of a portion of the crane and showing the pivotal portion of the revolute arm mounted thereon. Fig. 75 8 is a transverse section through the parts shown in Fig. 7.

Referring to the figures by characters of reference, A designates a car body in the door a of which is arranged a rock bar 1 extending 80 transversely of the door and mounted in suitable bearings 2. This bar carries the usual bag gripping fork 3 having a combined handle and counterbalance 4 extending into the car whereby the same may be conveniently manipulated. This fork can be made reversible so as to properly engage a suspended bag when the car is traveling in either direction.

Secured to the wall of the car adjacent op- 90 posite sides of the door a are superposed tubular brackets 6 and 7 each of which has notches or recesses 8 and 9 in its upper end for the purpose hereinafter explained.

An arm 10 extends outwardly from the 95 car and has a neck or trunnion 11 extending downward from one end and journaled within the bracket 7. A lug 12 extends from this trunnion and is designed to normally rest upon the bracket 7 but, when the arm is 100 swung outwardly from the door of the car this lug will be brought against a shoulder 13 constituting an extension of one wall of the notch 9 and will drop into said notch and thus lock the arm extended at right angles 105 to the car. The notch 8 is so positioned that when the lug 12 is raised out of notch 9 and shifted so as to drop into the notch 8 the arm 10 will be held practically parallel with the wall of the car. A flange 14 is formed upon 110 the bracket 7 below notches 8 and 9 and is for the purpose hereinafter set forth.

A brace 15 extends upwardly from the outer end of arm 10 and is preferably formed integral therewith, said brace being provided at its free end with a downwardly extending neck or trunnion 16 bearing within the bracket 6. A lug 17 extends from this trunnion and is designed to drop into either the notch 9 or the notch 8 formed therein, according to the position occupied by the arm 10 and brace 15. The notches in this upper bracket are arranged in the same manner as are those in the lower bracket 7. Said upper bracket is also formed with a longitudinal slot 18 and a holding pin 19 extends from the end portion of the neck 16. This slot 18, when arm 10 is in a predetermined position, permits the pin 19 to slide upward therethrough and this allows arm 10 and its brace 15 to be removed. The inner portions of arm 10 and brace 15 are preferably connected by means of a brace 20.

Members 21 extend downward from the arm 10 and constitute bearings for a rock bar 22. Suitable means such as collars 23 are provided upon the rock bar to prevent longitudinal movement thereof, and a tripping arm 24 depends from the outer end of the bar. At an intermediate point the rock bar is provided with a recess 25, the longitudinal wall 30 of which is concaved transversely as shown particularly in Fig. 3, the longitudinal center of this wall being disposed along the longitudinal axis of the rock bar.

Plates 26 are secured in any suitable manner to opposite faces of arm 10 and to each of these plates is hingedly connected a supporting finger or strap 27 either one of which is designed to rest loosely within the recess 25 with its free end bearing upon the longitudinal center thereof. It is to be understood that either of these fingers can be placed within the recess but it is not intended to so position both of them at the same time.

A cam 28 is secured to the inner end of the rock bar 22 and bears upon flange 14. This cam, as indicated in Fig. 4, is so shaped that when the rock bar is partly rotated in either direction the cam will bear upon the flange and lift the rock bar and arm 10 so as to raise the lugs 12 and 17 out of the notches 9 should they be seated therein. A spring 29 is detachably secured at its ends to the arm 10 and to the wall of the car and it is designed to hold said arm normally in position against the car and with lugs 12 and 17 seated in notches 8.

Buttons 30 are secured upon opposite faces of arm 10, there being preferably two upon each face. These buttons are designed to project into angular key-hole slots 31 formed in a plate 32 which may thus be detachably fastened to either face of the arm 10. This plate has elongated fingers 33 depending therefrom and they are for the purposes hereinafter set forth.

As indicated in Fig. 1 two sets of brackets 6 and 7 are provided, one set being located adjacent each side of the door *a* so that the arm 10 and the parts connected thereto may be readily fastened to the car at either side of the door so as to permit the mechanism to operate in the same manner when the car is moving in either direction.

The means employed for receiving a bag from the delivering mechanism carried by the car consists of a standard 34 which may be mounted on the platform 35. This standard has collars 36 and 37 arranged thereon and revolvably mounted between these collars is a sleeve 38 formed at one end of an arm 39 which extends at right angles from the standard and is provided with a double fork 40, such for example, as shown in Fig. 1 which is designed to engage a bag supported from the arm 10 whether said bag is approaching the fork from either direction. Anti-friction devices such as balls 41 are preferably interposed between sleeve 38 and collar 37 so as to permit the arm 39 to readily swing in a circle as a result of the impulse imparted to it by the sudden contact of a moving bag with the fork 40. In order that this movement of the arm 39 may be initially retarded to a sufficient degree to insure the proper actuation by arm 39 of the bag releasing mechanism on the car, a roller 42 is interposed between sleeve 38 and collar 37, the same being located at one end of a spring 43 fastened to an extension 44 on collar 37. This roller is held projected by the spring 43 into a recess 45 formed in the lower face of sleeve 38. When the roller is thus positioned the arm 39 is extended toward the track. A brace 46 preferably extends downward from arm 39 and has a ring 47 at its free end which loosely embraces the standard 34 and is designed to rotate thereon.

When it is desired to deliver a bag from a car the delivering mechanism is positioned adjacent that side of the car door *a* nearest the rear end of the car, this depending of course upon the direction in which the car is moving. The bag to be delivered, and which has been indicated by dotted lines at *B* in Fig. 1, is then supported by inserting one of the fingers 27 into the ring *b* located at the upper end of the bag. Said finger is then placed with its free end in the recess 25 as indicated in Fig. 3, the ring *b* bearing against the adjoining bearings 21 (see Fig. 2), this being permitted in view of the fact that these bearings are disposed at a distance apart slightly less than the diameter of the ring. This operation is performed while arm 10 is in position partly across the door *a* and as soon as the bag has been secured in the manner described arm 10 is released and spring 29 will swing it outwardly until lugs 12 and 17 come into contact with the shoulders 13, whereupon the arm 10 and its brace

15 will drop by gravity so as to seat said lugs within the notches 9. Arm 10 will therefore be held extended at right angles to the side of the car. Arm 24 extends vertically 5 downward and the cam 28 has its intermediate portion resting upon the flange 14.

As the car approaches the point of delivery arm 24 comes into contact with arm 39 with sufficient force to cause bar 22 to partly rotate and thus permit the end of the supported finger 27 to slip out of recess 25 and release the ring *b* of bag B. At the same time said bag is engaged by the fork 40 on arm 39 and supported thereby. The impact of the bag 15 against the fork 40 will cause the same to promptly swing horizontally with standard 34 as a center and the released bag will thus be swung away from the car. It is of course to be understood that roller 42 bears within 20 recess 45 with sufficient force to hold arm 39 in place while tripping the arm 24. When the bag B is brought into position within the fork 40 the force exerted thereby will be sufficient to swing the arm 39 and cause 25 roller 42 to become depressed and thus shift it out of the recess 45. Simultaneously with the release of bag B in the manner hereinbefore set forth the cam 28 is swung with the bar 22 so as to push against the flange 14. 30 The amount of rotation necessary to release bag B will also be sufficient to move the cam 28 the distance necessary to lift bar 22 and arm 10 such a distance as to raise the studs 12 and 17 out of notches 9. As soon as 35 these studs have been raised out of these notches and above the shoulders 13 the tensioned spring 29 will swing arm 10 inwardly toward the car wall until the studs are brought above notches 8 into which they 40 will promptly drop and thus lock the apparatus against the side of the car.

While bag B is suspended by one of the fingers 27 the rear portion thereof contacts with the fingers 33 which act as braces to 45 prevent the bag from swinging rearwardly as a result of the forward movement of the car and the resistance offered by the atmosphere.

Although mechanism has been shown 50 whereby the delivered bag can be engaged by a fork 40, it is to be understood that if preferred a fixed arm may be used instead of the swinging arm 39, said arm being merely employed to trip the depending arm 24 55 whereupon the released bag will fall to the ground or into a bin or other suitable receptacle provided for it.

Importance is attached to the fact that the fingers 27 are designed to rest at their 60 free ends upon the longitudinal center of the wall of recess 25, said longitudinal center alining with the axis of the rock bar 22. As a result of this arrangement it will be apparent that when the rock bar is partially rotated to release a bag it does not lift the

finger or consequently raise the bag supported by it. The apparatus can thus be very readily operated. It will also be seen that it is absolutely impossible for the bag to become accidentally released from its supporting structure because this necessitates the rotation of bar 22. 70

By duplicating the brackets at opposite sides of the car door and by constructing the arm 10 in the manner described it becomes possible to place said arm at either side of the door so that it will operate in the same manner when the car is moving in either direction and will at no time obstruct the door of the car. 75

The pin 19 heretofore referred to constitutes efficient means to prevent the arm 10 and its brace 15 from jumping out of their brackets 6 and 7. When, however, this pin 19 is swung in position below the slot 18, 80 as when the arm 10 is extending across door *a*, said arm and its brace can be lifted out of engagement with its bracket.

What is claimed is:

1. In apparatus of the character described 90 delivery mechanism comprising a movable arm, means for holding the arm against movement, bag engaging means carried by the arm, and revoluble means upon the arm for simultaneously releasing the arm from its holding means and unlocking said bag engaging means.

2. In apparatus of the character described, 95 delivery mechanism comprising a spring actuated arm, means for holding said arm 100 against the stress of the spring, bag engaging means carried by the arm, and a revoluble device upon the arm for simultaneously unlocking said means and releasing the arm from its holding means.

3. In a device of the character described, 105 delivery mechanism comprising a spring actuated arm, means for holding the arm against the stress of the spring, bag engaging means pivotally connected to and depending from the arm, a revoluble locking device normally supporting said bag engaging means and carried by the arm, and a revoluble releasing cam upon the arm for engagement with the holding means.

4. In apparatus of the character described, 110 delivery mechanism comprising a spring actuated arm, means for engaging the arm to hold it against the stress of the spring, a bag engaging member pivotally connected to the arm and depending therefrom, a rock device carried by the arm and having a recess for the reception of said member, an arm lifting device carried by the rock device, and a tripping arm depending from said device. 120

5. In apparatus of the character described, 125 delivery mechanism comprising a spring actuated pivot arm, means disposed to engage the arm to hold it against the stress of the spring, a recessed rock device carried by 130

the arm, a pivoted bag engaging member carried by the arm and having one end normally seated within the recess along the longitudinal axis of the rock device, and means carried by said device for disengaging the arm and holding means.

6. In apparatus of the character described, delivery mechanism comprising a spring actuated horizontally movable pivoted arm, means for holding said arm against the stress of the spring, a rock device mounted upon the arm and having a recess, a bag engaging member pivotally connected to the arm, the free end of said member being disposed to rest within the recess along the axis of the rock device, and means carried by the rock device for unlocking the arm.

7. In apparatus of the character described, the combination with a standard having an outstanding member; of mechanism comprising a spring actuated arm, means for holding said arm against the stress of the spring, a rock device carried by the arm and having a recess, a bag engaging member pivotally connected to the arm and disposed to rest at one end within the recess and along the axis of the rock device, a tripping arm extending from said device and into the path of the projecting member of the standard, and means carried by the rock device for unlocking the arm from its holding means.

8. The combination with a standard, a bag receiving member mounted to swing thereon, and means for initially retarding the movement of said member; of delivery mechanism comprising a spring actuated arm, means for holding said arm normally against the stress of its spring, bag engaging means carried by said arm, a locking device for said means and disposed to be actuated by the projecting member of the standard to release said means, and means carried by the locking device for disengaging the arm from its holding means simultaneously with the release of the bag.

9. In apparatus of the character described, the combination with a standard, and a member projecting therebeyond; of delivery mechanism comprising a pivotally mounted spring actuated arm, bag holding and releasing mechanism carried thereby, a cam movable with the releasing mechanism, means for holding the arm against the stress of its spring, a fixed bearing for the cam, and means operated by the co-operation of the outstanding member and the releasing mechanism for actuating the cam to lift the arm out of engagement with its holding means.

10. In apparatus of the character described, delivery mechanism comprising a spring actuated swinging arm, bearings therefor, means carried by the arm for engaging the bearings to lock the arm in a predetermined position and against the stress of the spring, and bag engaging and releasing mech-

anism carried by the arm and disposed to lift the arm from its holding means.

11. In apparatus of the character described the combination with a bearing member, an arm journaled therein, and means carried by the arm for engaging the bearing member to lock the arm in a predetermined position; of means for automatically actuating the arm when released from its locking means, bag engaging and releasing means carried by the arm, and means operating simultaneously therewith for lifting the arm to disengage it from the bearings.

12. In apparatus of the character described the combination with a supporting structure; of an upwardly movable bag supporting member hingedly connected to said structure, means for automatically swinging said member in one direction, means disposed to be automatically engaged by said member for holding said member against the action of said actuating means, bag releasing means carried by said member, and means operated thereby for lifting said member to release it from its holding means.

13. In apparatus of the character described delivery mechanism comprising a spring actuated arm, bag supporting and releasing mechanism carried thereby, means for holding the arm against the action of the spring, and lifting means operated by the releasing mechanism for simultaneously unlocking or disengaging the arm and its holding means.

14. In apparatus of the character described delivery mechanism comprising a spring operated arm, bag engaging and releasing mechanism carried thereby, depending bracing devices detachably carried by the arm, means for holding the arm against the action of its spring, and means for releasing the arm from its holding means.

15. In apparatus of the character described delivery mechanism comprising an arm, bag engaging means movably connected to the arm, a revoluble locking device normally supporting said means and carried by the arm, and a tripping arm extending from said device.

16. In apparatus of the character described the combination with a supporting structure; of an arm extending therefrom, bag engaging means movably connected to and depending from the arm, a locking device carried by the arm for supporting said means, means for rotating said device to release said bag engaging means, and a bag bracing device extending from the arm.

17. The combination with a supporting structure having a door; of a spring actuated arm, bag engaging means carried by the arm, a locking device upon the arm for engaging said means, means for holding the arm against the action of its spring, means operated by the movement of the locking device for lift-

ing the arm from engagement with its holding means, and means upon the structure for operatively holding the arm at either side of the door.

- 5 18. In apparatus of the character described the combination with superposed bearing members, each member having notches therein and a shoulder interposed between the notches; of an arm pivotally mounted within one of the bearing members, a brace extending from said arm and removably mounted within the other bearing member, separate engaging means carried by the arm and brace for successively engaging the 15 notches in the respective bearing members, said shoulders being normally disposed in the path of said means, a spring for actuating the arm and brace, bag engaging and releasing means carried by the arm, and means operated by said mechanism for shifting the engaging means out of the notches within the bearing members to release the arm.
19. The combination with a bearing member having a notch therein, and a fixed flange 25 extending from said member; of an arm pivotally mounted within said member, an engaging device carried by the arm and disposed to be seated within the notch, bag engaging and releasing mechanism carried by 30 the arm, and a cam movable with said mechanism and bearing upon the flange to lift the arm and remove its engaging means from the notch, and means for swinging the arm when raised by the cam.
- 35 20. In apparatus of the character described the combination with an arm and bag holding means carried thereby, of a plurality of bag bracing devices depending from and detachably connected to the arm.
- 40 21. In apparatus of the character described delivery mechanism comprising an

arm, bag engaging means carried thereby, and bracing means for the bag comprising a strip detachably connected to the arm and a plurality of depending fingers upon the strip 45 and disposed to back the bag.

22. In apparatus of the character described delivery mechanism comprising a bearing member, an arm mounted thereon, means carried by the arm for engaging the bearing member to lock said arm in a predetermined position, a cam carried by said means, means coöperating with the cam to lift said arm when the cam is partly rotated, and means for actuating the cam. 55

23. In apparatus of the character described delivery mechanism comprising a bearing member, an arm mounted thereon, means carried by the arm for engaging the bearing member to lock said arm in a predetermined position, a cam carried by said means, means coöperating with the cam to lift said arm when the cam is partly rotated, means for actuating the cam, and means for automatically swinging the arm upon its 60 bearing member immediately subsequent to the actuation of the cam.

24. In apparatus of the character described delivery mechanism comprising an arm, a recessed rock device carried by the 70 arm, a bag engaging member movably connected to the arm and having one end normally seated within the recess and along the longitudinal axis of the rock device, and a trip device carried by the rock device. 75

In testimony that I claim the foregoing as my own, I have hereto affixed my signature in the presence of two witnesses.

ROBERT RAY ROTH.
